UNITED STATES PATENT OFFICE.

RUFUS KING, OF PLAINVILLE, MASSACHUSETTS, ASSIGNOR TO BUGBEE AND NILES CO.,
OF NORTH ATTLEBORO, MASSACHUSETTS, A CORPORATION OF MASSACHUSETTS.

DESIGN FOR A CLASP OR BUCKLE FOR STRAPS OR RIBBONS OF WRIST-WATCHES.

51,861.

Specification for Design.

Patented Mar. 12, 1918.

Application filed January 7, 1918. Serial No. 210,782. Term of patent 3½ years.

To all whom it may concern:

Be it known that I, RUFUS KING, a citizen of the United States, residing at Plainville, in the county of Norfolk, State of Massachusetts, have invented a new, original, and ornamental Design for a Clasp or Buckle for Straps or Ribbons of Wrist-Watches, of which the following is a specification, reference being had to the accom-

panying drawing, forming a part thereof, in which—

Figure 1 is a plan view; and
Fig. 2, an end view.

I claim:—

The ornamental design for a clasp or buckle for straps or ribbons of wrist watches, as shown.

RUFUS KING.
